Inventor, a/c.

UNITED STATES PATENT OFFICE.

ALEXANDER JEFFERSON JERNAGAN, OF STARRVILLE, TEXAS, ASSIGNOR OF
SIX-EIGHTHS TO ALBERT MARSHALL CLINKSCALES AND BENJAMIN
IREDELL EGERTON, OF SAME PLACE.

CAR-COUPING.

SPECIFICATION forming part of Letters Patent No. 326,085, dated September 8, 1885.

Application filed December 29, 1884. (No model.)

To all whom it may concern:

Be it known that I, ALEXANDER JEFFERSON JERNAGAN, a citizen of the United States, residing at Starrville, in the county of Smith 5 and State of Texas, have invented certain new and useful Improvements in Car-Couplers; and I do hereby declare the following to be a full, clear, and exact description of the invention, such as will enable others skilled in 10 the art to which it appertains to make and use the same.

This invention relates to that class of car-couplers in which are used two spring latch-catches for coupling.

15 The object of my invention is to facilitate the coupling of cars, prevent the loss and maiming of persons engaged in coupling them, and as well to obviate the expense engendered by the old pin-and-shackle system.

20 To this end my invention consists in novel features and combinations, which will be fully set forth in the ensuing specification, and by means of which it automatically couples itself.

25 In the accompanying drawing the figure is a side representation of two of my draw-heads connected by my improved coupler.

The same letters of reference indicate identical parts.

30 The draw-head F is substantially the same as those now in use. These draw-heads connect by means of two spring latch-catches in each draw-head. The latch-catches B close over a rod at e'. The latches are held in draw-

head by a rod the same as that over which 35 they catch. This rod is shown by b. Thus it may be seen that should both springs of either draw-head be broken, and not those of the other, they would yet be held strongly enough to bear any ordinary strain. 40

For uncoupling, a hand-lever is used, which is shown at A, to which is attached a chain, d, which chain is fastened to the latch. This is the same in each draw-head. The brake-spring is shown at a. The lever is supported 45 when the draw-heads are uncoupled by a spring, f, and this spring is supported by a spiral spring, e.

This automatic coupling is so simple in construction and its manner of operation that it 50 is unnecessary to prolong this explanation.

What I claim as my invention is—

1. A hand-lever and two chains as used in combination with the spring-latch catches.
2. A brake-lever attached to main lever, a 55 spring and spiral to hold said main lever in place, and a chain to main lever attached to the spring latch-catches aforesaid of each draw-head.

In testimony whereof I affix my signature 60 in presence of two witnesses.

ALEXANDER JEFFERSON JERNAGAN.
